No. 36,868.

Patented April 5, 1904.

UNITED STATES PATENT OFFICE.

MARSHALL W. GLEASON, OF NEW YORK, N. Y.

DESIGN FOR A GLASS GLOBE.

SPECIFICATION forming part of Design No. 36,868, dated April 5, 1904.

Application filed February 24, 1904. Serial No. 195,115. Term of patent 3½ years.

To all whom it may concern:

Be it known that I, MARSHALL W. GLEASON, a citizen of the United States, residing at New York city, in the county of Kings and State of

5 New York, have invented a new, original, and ornamental Design for a Glass Globe, of which the following is a specification, reference being had to the accompanying drawings, forming part thereof.

10 Figure 1 is a side view, and Fig. 2 is an inverted plan view, of the globe.

What I claim as new, and desire to secure by Letters Patent, is—

The ornamental design for a glass globe, as shown.

MARSHALL W. GLEASON.
